ASH REMOVAL APPARATUS

Charles K. Birch, Montclair, N. J., assignor to
Lehigh Valley Coal Sales Company, New York,
N. Y., a corporation of Delaware

Application March 19, 1949, Serial No. 82,341

2 Claims. (Cl. 302—36)

1

This invention is directed to the provision of improved ash removal apparatus for transferring ashes from a coal-fired furnace to an ash receptacle located at a distance from the furnace. The new apparatus makes use of a suction system for effecting transfer of the ashes from a hopper beneath the furnace to the ash receptacle. Suction systems for ash removal have been proposed heretofore, but have not been generally accepted for use in connection with small furnaces such as household heating furnaces. A careful study of the capabilities and limitations of suction systems has led me to the conclusion that such systems are in principle sound for eliminating the hard and dirty job of removing ashes by hand from a coal-fired furnace; but for the system to be practically useful special provisions must be made to prevent clogging, and the system must be essentially automatic in its operation in order for it to be suitable for widespread use, and especially for use with furnaces for household heating and with other furnaces operated by mechanically untrained persons. Lack of effective provisions to accomplish these ends have been responsible for the indifferent success of the suction systems for ash removal heretofore proposed.

The ash removal system of the invention is particularly designed to minimize any opportunity for clogging, to be quiet and clean in its operation, to be essentially automatic, and to be constructed at a cost making it attractive for use in conjunction with household heating furnaces and other small coal-fired furnace installations. The complete apparatus of the invention comprises a coal-fired furnace having an ash crushing grate provided with the usual grate shaking lever, which in turn is equipped with a removable shaking lever handle. An ash hopper is mounted beneath the grate to receive ashes shaken therethrough. A suction box is connected to the bottom of the hopper, and the hopper serves to direct the ashes into it. The suction box is connected by a suction pipe to an ash separator detachably mounted on an ash receptacle located at a distance from the furnace and in which the ashes ultimately are collected. A suction fan, preferably mounted directly on the ash separator, is arranged so that its inlet is connected therewith. Its outlet may be connected to a discharge vent or flue, or may be connected to a dust filter, or may simply open directly to the atmosphere. The fan is driven by an electric motor which preferably is energized through a switch mounted adjacent the grate

shaking lever and connected in circuit with a motor and with a source of electric power. If such a switch is used, means for closing it are mounted on the grate shaking lever in position to be engaged and actuated by the removable handle whenever the latter is attached to the grate shaking lever. Thereby whenever the handle is applied to the shaking lever, the fan motor is automatically energized and creates a flow of air from the ash hopper through the suction box and suction pipe to the ash separator. Shaking the grate crushes the ashes as well as causing them to fall into the hopper, whence they are carried in the air stream through the suction pipe to the ash separator. There the coarse ashes separate from the air stream and settle into the receptacle. Thus the system is automatically set in operation and the ashes are transferred to the receptacle by the simple steps of placing the handle on the grate shaking lever and shaking it in the usual manner.

The design of the grate is of importance to the operation of the system as a whole, for it must be capable of crushing whatever ashes pass through it, when it is shaken, to a size fine enough so as not to cause clogging of the suction system. Also of importance to the operation of the system as a whole is the design and construction of the suction box at the bottom of the hopper. Even fine ashes tend to accumulate at this point and cause the suction pipe to become clogged; but I have found that by providing a suction box of proper design at the bottom of the hopper, to which the suction pipe is connected, clogging can be virtually completely prevented. Furthermore, the provision of a suction box permits the suction pipe to extend laterally from it, rather than vertically down from the hopper, and so greatly decreases the head room required below the grate for installing the system. The arrangement of the suction fan and ash separator directly over the ash receptacle renders operation of the system clean in the building within which the furnace is located by making the entire system within such building, up to the ash receptacle itself, operate under a reduced pressure and so prevent the possibility that leaks in the system will result in ash dust being discharged into the building atmosphere. Also by this arrangement the noise incident to operation of the fan is produced at a point where it is not objectionable.

The foregoing and other features of the new apparatus are described more in detail below with reference to the accompanying drawings,

which show a preferred embodiment of the new apparatus and in which

Fig. 1 is a more or less diagrammatic view, partially in section, of an ash removal system according to the invention; and

Fig. 2 is a plan view looking down on the ash hopper of the furnace of Fig. 1.

The ash removal apparatus of the invention is shown in Fig. 1 in combination with a coal-fired furnace 10. The furnace is provided with a grate 11 on which the coal is burned. A grate shaking lever 12 fitted with a removable handle 13 is provided for shaking the grate and thereby causing the ash to drop into a hopper 14 mounted directly beneath the grate. A suction box 15 is connected to the bottom of the hopper, and one end of a suction pipe 16 is in turn connected to the bottom of the suction box. The other end of the suction pipe connects with an ash separator 17 detachably mounted on an ash receptacle 18. In most installations the ash receptacle will be located at a distance from and at a higher level than the furnace 10. A fan 19 is mounted over the ash separator, with its inlet conduit 20 connected with the interior of the separator. The outlet conduit 21 from the fan is connected to a discharge vent or flue 22, or may alternatively be connected to a dust filter bag, or even be open to the atmosphere. The fan is driven by an electric motor 23.

When the fan motor 23 is energized, the fan draws air from the hopper 14 through the suction box 15 and suction pipe 16 into and through the separator 17. Ash delivered through the grate 11 when the latter is shaken is collected in the current of air in the suction box and is transferred thereby to the separator, wherein almost all of the ash settles out and drops into the receptacle 18. The small amount of fine ash particles that do not settle are carried in the air stream through the fan and through its outlet conduit 21 to the discharge vent 22. The air escapes through the pores of the filter bag to the atmosphere.

It is necessary that the ash entering the hopper 14 be finely enough divided so as not to clog the suction box 15 or the suction pipe 16. Accordingly, the grate 11 is designed to crush the ash passing through it into the hopper. An advantageous form of grate is shown in my copending application Serial No. 135,000, filed September 15, 1950.

The ash hopper 14 is supported directly below the grate 11 on brackets 30 fastened to the furnace structure. The hopper is defined by a substantially plane front wall 31, a substantially plane rear wall 32, and substantially plane side walls 33, all of which walls slope inwardly and downwardly toward each other. The suction box 15 at the bottom of the hopper is most advantageously formed by extending the front wall 31 and side walls 33 of the hopper substantially in their respective planes downwardly to a bottom apex 34 beneath the bottom of the hopper itself (the bottom of the hopper is demarcated by the lower edge 35 of the hopper rear wall 32). The rear wall 36 of the suction box (as best shown in Fig. 1) is curved concavely toward the front wall; i. e., its lower portion near the suction box apex 34 curves upwardly and away from the front wall, and its upper portion curves back again toward the front wall and joins with the rear wall 32 of the hopper at its lower edge 35. Thus the rear wall of the suction box approaches the front wall thereof more closely at its upper

edge than at its mid-portion, and the maximum distance between the front and rear walls of the suction box occurs substantially midway between the top and bottom edges of such rear wall. The suction pipe 16 is connected to the front wall of the suction box 15 near its bottom apex, and extends laterally therefrom at an acute angle thereto.

I have found that the provision of a suction box 15 is of importance to prevent clogging of the suction system. If the suction box is omitted and the suction pipe is connected directly to the bottom of the hopper (especially if it extends laterally therefrom), the ash that collects at the bottom of the hopper tends to clog the entrance to the suction pipe. It is my present belief that when a suction box as described above is provided, it has the effect of so directing the current of air created by the suction fan as to avoid or minimize any regions of low air velocity in which ash particles tend to settle out and collect in a pipe-clogging mass. In any event, the provision of the suction box is of distinct advantage, both for its effect in preventing clogging and because it enables the suction pipe to extend laterally from beneath the furnace, thereby minimizing the space required beneath the grate for making the installation.

The ash separator 17 to which the other end 30 of the suction pipe 16 is connected is simply a chamber, preferably cylindrical, closed at the top and open at the bottom. A flange 37 is provided about its lower periphery for engaging with the upper edge of the ash receptacle 18. The flange may be lined with gasket material to facilitate making a tight joint with the receptacle. The ash separator may be permanently mounted in position, and the ash receptacle may be carried on a vertically movable platform that may be raised to bring the upper edge of the receptacle into engagement with the flange 37 to form a substantially pressure-tight joint during normal use of the apparatus, and that may be lowered when desired through the distance of several inches necessary to permit withdrawal of the receptacle when it is time to empty it. Alternatively the ash receptacle may be set on a rigid floor and some special provision may be made for raising and lowering the ash separator, or the separator may merely rest on the receptacle, to be manually raised and lowered.

The fan inlet conduit 20, which is open at its lower end, extends axially into the ash separator through its closed top and projects preferably to a point near its open bottom. The suction pipe 16, on the other hand, is preferably connected to the side of the ash separator near its top. The separator provides a substantial enlargement in the suction system, in which the velocity of the air current created by the fan is low and in which ash particles carried by the current of air are consequently given an opportunity to settle out and fall into the ash receptacle. Generally it is advantageous to connect the suction pipe 16 tangentially rather than radially to the ash separator, so that the direction of air flow through the separator is more or less circular. This results in imparting a centrifugal force to the ash particles and thereby promotes their separation from the current of air.

The fan 19 is of conventional construction. Whatever very fine ash does not settle out in the separator 17 (and it is quite small in amount) is carried by the current of air through the fan

and is discharged through the vent 22. In some cases the vent 22 may be dispensed with and the fan outlet may discharge directly to the atmosphere. In other cases where conditions require catching even the very small amount of fine ash that does not settle in the separator, a filter bag may be attached to the fan outlet conduit 21.

In a typical installation of the new apparatus in combination with a household heating furnace, the furnace itself is located in the basement of the building, and the ash receptacle, the separator, and the fan are located some distance away at ground level, whence it is relatively easy to carry away the ash receptacle, when it is full, for the purpose of disposing of the ashes.

In order to minimize any opportunity for clogging of the system, it is important to transfer the ashes to the receptacle substantially as soon as they are passed through the grate into the hopper, and to avoid having them collected and stored, even for but a short period of time, in any part of the system between the grate and the receptacle. This involves making provision to operate the fan whenever the grate is shaken. A convenient way to accomplish this result essentially automatically is to actuate the motor 23 (which drives the fan) through a normally open switch which is closed (to set the fan in operation) when the removable handle 13 is placed on the grate shaking lever 12.

It is evident from the foregoing that the ash removal system of the invention is of uncomplicated construction, is easy to install, and is substantially automatic in its operation (i. e. it requires no manipulative steps beyond those normally involved in shaking the grate of a coal-fired furnace). It has also been found in use to be effective for removing ordinary coal ashes from a furnace to a receptacle remote from and at a substantially higher elevation than the furnace itself; and it has proved to be reliable and dependable. It therefore provides a practical means for eliminating the most objectionable feature incident to the operation of small coal-fired furnaces, namely, the removal by hand of the ashes.

I claim:

1. In ash removal apparatus of the character

described, an ash hopper, a suction box connected to said hopper at the bottom thereof and having side walls and a front wall inclined downwardly to a bottom apex, an ash removal suction pipe connected to and extending substantially laterally from the front wall of said suction box at the bottom thereof and at an acute angle thereto, the suction box having a closed rear wall the lower portion of which extends to the bottom of the suction pipe and curves away from the front wall and the upper portion of which curves back again toward the front wall, the maximum distance between the front wall and rear wall being at a point below the top edge of said rear wall and above the bottom apex of the suction box.

2. In ash removal apparatus of the character described, an ash hopper having substantially plane front, side and rear walls all sloping downwardly toward each other, said front and side walls being extended substantially in their respective planes to below the bottom of the hopper and forming the front and side walls of a suction box having a bottom apex and connected to said hopper at the bottom thereof, and a closed rear wall for said suction box joined at its upper edge to the lower edge of the hopper rear wall, the rear wall of the suction box being curved concavely toward the front wall thereof and extending to the apex of the suction box, the maximum spacing between the front and rear walls of the suction box being approximately midway between the top edge of said rear wall and the bottom apex of the suction box.
